UNITED STATES PATENT OFFICE.

BASIL NEFEDOV, OF BROOKLYN, NEW YORK.

WHEELED TOY.

Application filed October 6, 1921. Serial No. 505,834.

To all whom it may concern:

Be it known that I, BASIL NEFEDOV, a citizen of Russia, and a resident of the city of New York, borough of Brooklyn, in the 5 county of Kings and State of New York, have invented a new and Improved Wheeled Toy, of which the following is a full, clear, and exact description.

This invention relates to improvements in 10 toys, an object of the invention being to provide a toy aeroplane mounted upon wheels and provided with a sail so that the toy will be blown over the ground.

A further object is to provide a toy of 15 this character formed in several interfitting sections which may be disassembled permitting the top to be packed in a relatively small space.

Still another object of the invention is to 20 provide a toy which will be simple and practical in construction, durable and efficient in use, attractive in appearance and comparatively inexpensive to manufacture.

With these and other objects in view, the 25 invention consists in certain novel features of construction and combinations and arrangements of parts as will be more fully hereinafter described and pointed out in the claims.

30 In the accompanying drawings:

Figure 1 is a view in side elevation of my improved toy;

Figure 2 is a view in front elevation thereof;

35 Figure 3 is a fragmentary sectional view on the line 3—3 of Figure 1; and

Figure 4 is a sectional view on the line 4—4 of Figure 1.

Referring in detail to the drawings, my 40 improved toy comprises an elongated body portion 1, simulating in appearance to a fuselage of an aeroplane. A propeller 2 is mounted on the forward end of the body portion and a laterally extending tail 3 is 45 formed from a sheet of suitable material attached at its forward end to the rear of the body 1. A traction wheel 4 is journaled upon a suitable shaft 5 mounted in a recess in the extreme rear end of the body.

50 I have used the reference numeral 6 to designate a transverse frame detachably associated with the forward end of the body portion, and including laterally extending arms 7, at the extremities of which, traction 55 wheels 8 are mounted. A recess 9 in the up-

per edge of the intermediate portion of the frame 6 cooperates with a similar recess in the bottom of the body portion to permit the interfitting of the body portion and frame in a customary and well known manner, as seen most clearly in Figure 4.

The representation of a driver 10 may be secured in a curved recess 11 in the top of the body portion in any approved manner. A vertical slit or recess 12 in the top of the body portion immediately behind the driver provides a place of attachment for a relatively wide plane or sail 13. The plane preferably comprises a sheet of relatively thin light metal, to which a vertical channeled reinforcing bar 14 is attached. In applying the plane to the body portion, the lower edge of the plane proper and the intermediate portion of the channeled member are introduced into the slot 12, the sides or arms of the channeled member embracing the body portion, as seen clearly in Figure 3 and bracing the plane against accidental displacement.

It will be apparent that the construction 80 of the plane and its method of attachment to the body portion might be considerably varied without departing from the spirit of the invention which is broad enough to cover a plane applied in any manner to a 85 rolling toy.

In using the toy, the child places the toy upon the ground and it is blown by the wind. It will be noted that the traction wheels are spaced a sufficient distance apart to prevent 90 accidental overturning of the toy.

Although I have illustrated the preferred embodiment of my invention, certain slight changes and alterations might be made in the general form and arrangement of the 95 parts described without departing from the invention, and hence I do not wish to limit myself to the precise details of construction, but shall consider myself at liberty to make such slight changes and alterations as fairly 100 fall within the spirit and scope of the appended claims.

I claim:

1. As a new article of manufacture, a toy 105 including an elongated body portion, a transverse frame detachably interfitting therewith, wheels at the extremities of the frame, a wheel at the rear end of the body portion, and a plane detachably mounted on the body portion, said plane including a sheet of light 110

metal and a channeled bracing bar carried thereby, said body having a slit in its upper edge receiving the lower edge of the sheet and intermediate portion of the lower end 5 of the channeled member, whereby to support said plane in vertical position.

2. A toy comprising a body consisting of a strip of material having a notch in its under side, a transverse frame having a notch in 10 its upper side adapted to interfit the notch in the body, wheels at the outer extremities of said frame, a wheel at the rear end of said body, and a vertical plane detachably carried by the body, said plane including a 15 sheet of material having a central vertical brace, the said body having a slit in its up-

per edge receiving the lower edge of the plane and the brace.

3. As a new article of manufacture, a 20 toy including a wheeled body consisting of a strip of material having a transverse slit in its upper edge, and a plane including a sheet of material having a central vertical brace with side flanges on said brace extending at right angles to the plane and parallel 25 to each other, the lower edge of said plane and the brace being received by the slit with the side flanges of the brace extending alongside the body to maintain the plane in a vertical position.

BASIL NEFEDOV.
